(57) **CLAIM**

The ornamental design for a wearable device, as shown and described.

DESCRIPTION

FIG. 1 is a perspective view of a wearable device showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a reference view thereof showing the state of operating; and,

FIG. 9 is a reference view showing an example of the usage of the subject design in which the subject design is unfolded and worn around the user's neck.

The broken lines in FIG. 9 showing a human figure represent environment and form no part of the claimed design. The remaining broken lines shown in FIGS. 8 and 9 represent portions of the wearable device which form no part of the claimed design.
